UNITED STATES PATENT OFFICE.

ALFRED ROSENFIELD, OF BERLIN, GERMANY.

GARMENT-CLOSURE.

1,114,185.

Specification of Letters Patent.

Patented Oct. 20, 1914.

Application filed December 24, 1910. Serial No. 599,083.

To all whom it may concern:

Be it known that I, ALFRED ROSENFIELD, a subject of the German Emperor, residing at Berlin, Germany, have invented a new and Improved Garment-Closure, of which the following is a specification.

This invention relates to a closing device for garments provided on opposite edges with spring buttons, hooks and eyes or similar fasteners. The device is so constructed that by being moved along the garment opening or slit on suitable guides, it will cause the opposed garment edges to be brought into superposition. In this way the coacting fastening members which are secured to the garment at the same distance from said edges are forced into a closing engagement.

In the accompanying drawing: Figure 1 is a front elevation partly in section of a garment closure embodying my invention; Fig. 2 a side view of the slides; Fig. 3 a bottom view of the upper slide member; Fig. 3^a a perspective view of the upper slide member; Fig. 3^b a perspective view of the lower slide member; Fig. 4 a detail of the spring button fastener; Fig. 5 a detail of a modification of the guide rail; and Fig. 6, a bottom view of a modification of the closure.

The closure comprises essentially a top plate 1 having a bulged section 1^a and an inwardly turned flange 1^b. To the lower face of plate 1, there is secured by lugs 5^a and pintle 5, a second plate 2 which partly underlies bulged section 1^a where it is provided with a slot 15. Plate 2 is separated at its left edge from the corresponding edge of flange 1^b by a slot 2^b having a laterally deflected end 2^c. At its right end plate 2 is turned downwardly and provided with tongues 9 engaging corresponding slits in a third plate 4, the right hand portion of which underlies the corresponding portion 45 of plate 1 and is removably connected thereto by a knob 10 engaging a corresponding aperture 10^a of a plate 1. The left hand portion of plate 4 is provided with forward and rear guide lugs 11, and with a pair of hinge knuckles 4^a, 4^b of which knuckle 4^a depends a less distance from plate 4 than knuckle 4^b. To knuckles 4^a, 4^b there is hinged a bottom plate 3, by means of a pair of pintles 5^b. This plate is provided with 55 a central inclined section A—B between its

parallel front and rear sections, so that in this way the rear section which is hinged at 4^a is in closer proximity to plate 4 than its front section which is hinged at 4^b.

In order to operate the device, the upper 60 slide member comprising the parts 1 and 2 is detached from the lower slide member comprising the parts 3 and 4 by withdrawing the connecting means 9 and 10. The upper garment flap 100 is provided with a 65 longitudinal fold 101 fixed by a stay 6 which is permanently sewed into the fold, so as to constitute a guide. This guide is introduced through slot 2^b into the clearance between plates 1 and 2, and thus constitutes a rail 70 along which the upper slide member may be moved along the upper garment fold. To garment flap 100 is further secured a suitable female fastening member such as a rigid plate 13 provided with a button hole 75 or elongated slot 13^a. The guide lugs 11 which are inclined are designed to raise the button hole member 13 between the plates 2 and 4, by projecting beneath the edge thereof, and forcing it upwardly during the 80 movement of the slide. Plate 13 is so placed with relation to the garment edge, that slot 13^a extends at right angles to such edge.

The lower garment flap 102 is provided with two similar guides comprising a pair 85 of parallel folds 103, 104 containing stays 7 and 8. To the fold 103 is attached a button or other male fastening member 14 adapted to engage button hole 13^a. If desired fold 104 containing stay 8 may be 90 omitted, the fold 103 with stay 7 being sufficient. To the lower side of the bottom flap 102, there may be secured a number of transversely arranged reinforcing ribs 12.

When the slide constructed as described 95 is moved along the flaps, the inclined section A—B of the lower slide member will raise the lower garment flap facewise up toward the upper flap, so that the button 14 is well drawn into the button hole 13^a, the passage 100 of the button through said hole being permitted by slot 15. After the engagement between button and button hole has thus been effected, the oblique section 2^c of the upper slide member will draw the upper 105 garment flap laterally away from the lower garment flap, so that the button is drawn into the button hole slit.

In Fig. 5 is shown a modification of the reinforcing stay inclosed within the garment 110

folds, the same being here shown to be made in the form of a sinuous wire 205.

I wish it to be understood that for conventional snap buttons, in which the eye has no lateral elongation, the lateral movement of the slide members may be dispensed with in which case the lateral deflection 2^c of slot 2^b is dispensed with as illustrated in Fig. 6.

10 I claim:

1. A garment closure comprising a slide having a flat bottom plate that is slidably arranged below a fold located on the lower garment-flap, said slide being provided with 15 longitudinal edges that engage the flap-bulges and are adapted to superimpose the two elements of a snap button or other flap closure.

2. A garment closure comprising a first 20 member adapted to slidably engage a first garment-flap, a second member carried by the first member and adapted to slidably engage a second garment-flap that extends below the first garment-flap, means on the second member for moving the garment-flaps facewise toward each other, and means on the first member for moving the first garment-flap laterally along the second garment-flap.

30 3. A garment closure comprising a first member adapted to slidably engage a first garment-flap having a female fastener provided with a contracted section, a second member carried by the first member and 35 adapted to slidably engage a second garment flap that extends below the first garment flap and is provided with a male fastener, means on the second member for moving the garment-flaps facewise toward 40 each other whereby the male fastener is brought into engagement with the female fastener, and means on the first member for moving the first garment-flap sidewise along the second garment-flap whereby the male

fastener is drawn into the contracted section of the female fastener.

4. A garment closure comprising a first slide member having a slot provided with a laterally deflected section, and a second slide member carried by the first member, and 50 bent to recede facewise from the first member.

5. In a garment closure a first slide member comprising an upper plate in which is formed a slot having a laterally deflected 55 section and a second plate having an opening, combined with a second slide member comprising a first plate that is removably secured to the first member, and a second plate having an inclined section that recedes 60 facewise from the first member.

6. In a garment closure a first slide member comprising an upper plate in which is formed a slot having a laterally deflected section, said slot being adapted to engage a 65 first folded garment flap that carries a female fastening device, and a second plate secured to the first plate and having an opening adapted to expose said female fastening device, combined with a second 70 slide member comprising a first plate that is removably secured to the first member, and a second plate hingedly secured to the first plate and having an inclined section, 75 that recedes facewise from the first member, said last named second plate being adapted to engage a second folded garment flap that carries upon the fold a male fastening device adapted to coöperate with said female fastening device.

In witness whereof I have hereunto signed my name in the presence of two subscribing witnesses.

ALFRED ROSENFIELD.
